UNITED STATES PATENT OFFICE.

HERMAN HANSEN, OF NEW YORK, N. Y., ASSIGNOR TO FRANCIS KEIL & SON INC., A CORPORATION OF NEW YORK.

LOCKING MECHANISM.

Application filed June 16, 1922. Serial No. 568,724.

My invention relates to a mechanism to be locked, the construction of which is adapted for many different uses where great security is desired.

5 The object of my invention is to provide a lock which is so constructed that a bolt operated thereby is rotated in order to bring a lateral projection thereon into engagement with a bolt-socket so as to prevent the direct longitudinal withdrawal of the same without previously rotating the bolt to disengage the lateral projection from the bolt-socket. Further objects of my invention will appear from the detailed description contained hereinafter.

10 While my invention is capable of embodiment in many different forms, for the purpose of illustration I have shown only one form thereof in the accompanying drawings, in which—

15 Figure 1 is a rear elevation of a lock made in accordance with my invention;

Fig. 2 is a front elevation of the interior 20 of the locking mechanism showing the lock in unlocked position;

Fig. 3 is a similar view showing the bolts extended before the rotation thereof;

Fig. 4 is another view of the same kind but showing the bolts after having been rotated;

25 Fig. 5 is an end elevation of the locking mechanism showing the bolts extended and after having been rotated;

Fig. 6 is a front elevation of the interior 30 of the lock casing showing the sliding plates removed;

Fig. 7 is a front elevation of the main sliding plate showing the two rotatable bolts attached thereto;

Fig. 8 is a side elevation of the same showing the bolts removed therefrom;

Fig. 9 is a front elevation of the auxiliary sliding plate;

Fig. 10 is a side elevation of the same;

Fig. 11 is a side elevation of the retaining plate used for holding the bolts in engagement with the sliding plates;

Fig. 12 is an elevation of the cover plate and the lock-operating lever thereon;

Fig. 13 is a side elevation showing the bolt-socket member;

Fig. 14 is a front elevation of the same;

Fig. 15 is a side elevation showing the key receiving barrel for operating the lock, the barrel casing for enclosing the same and a key for the lock;

Fig. 16 is a front elevation of the same showing the key removed; and

Fig. 17 is a side elevation of said key.

In the drawings, I have shown a key 1 adapted to extend into a barrel 2 arranged to 60 rotate within an outer casing 3 which has screw-holes 4 for securing the lock within the outer portion of a door. Within the barrel casing are the usual tumblers designed for controlling the rotation of a key 65 of this type. Secured to the rotatable barrel 2 there is a lock-operating arm 5 having an enlarged forward end 6 which is retained in engagement with the barrel 2 by means of a slotted disc 7 secured to the barrel 2 by 70 screws 8. The lock-operating arm 5, at its rearward end, engages with a slot 9 in a rotating arm 10 pivoted in a cover plate 11. Said arm 10, to operate the lock, is provided with a rearwardly extending eccentric pin 75 12 which is so positioned as to engage with a slot 13 in an auxiliary sliding plate 14 having lateral upper and lower guide flanges 15 guiding the said plate within a main sliding plate 16 provided with flanges 17 at the top 80 and bottom of the same which fit within guideways 18 in a lock-casing 19. At one side of the auxiliary sliding plate 14 there is an arm 20 extending through a slot 21 in the form of a cross located in a forward flange 85 22 on the main sliding plate 16, said arm 20 having upwardly and downwardly directed pins 23 and 24 to engage with upper and lower bolts 25 and 26 respectively which have spiral guideways 27 and 28 respectively 90 for engagement with said pins. The upper and lower bolts 25 and 26 are constructed alike except that the upper bolt 25 has a laterally directed stop 29 to cooperate with a projection 30 in the interior of the lock-casing 95 19 to prevent the rotation of the bolts except when fully extended, in the manner hereinafter described. Each of the said bolts 25 and 26 is provided with a T-shaped projection 31 which is engaged with the main sliding plate 16 by inserting the same through the slot 21 in the forward flange 22. Each of the said bolts, furthermore, has at 100 its outer end two lugs 32 at opposite sides of the bolt to engage within the interior of a bolt-socket member 33 adapted to be carried by the door casing, or frame, said bolt-socket member having a rectangular opening 34 in a plate 35. It will be noted that 105 said bolt-socket member has a plurality of 110

screw-holes 36 for attaching it to said door casing, or frame. It will be noted, also, that each of said bolts is provided with a core 37 of hardened steel to prevent the bolts from being sawed off when extended in locking position. When the main sliding plate carrying the upper and lower bolts 25 and 26 has been inserted into the lock-casing 19 by introducing the ends of the bolts through slots 38 in the side of the lock-casing and in such a manner that a pin 39 on an arm 40, adapted to be rotated by a knurled head 41 extending outwardly to the rear of the lock-casing, has been passed through a heart-shaped slot 42 in the main sliding plate 16, the auxiliary sliding plate 14 is introduced within the main sliding plate 16 in such a manner that the pins 23 and 24 pass through the cross-shaped slot 21 into engagement with the spiral recesses 27 and 28 on the bolts 25 and 26 and in such a manner as to bring the slot 13 over the pin 39. The arm 40, furthermore, has a slight extension 42^a cooperating with a spring 42^b supported within the lock-casing 19 in such a manner as to tend to retain the locking mechanism at one or the other end of its path of movement, so as to make the locking and unlocking movement smoother in operation. In order to hold the two sliding plates and tumblers in engagement in this manner a retaining plate 43, having two circular openings 44 fitting over the rear ends of the bolts 25 and 26 and a recess 45 fitting over the arm 20, is secured to the forward flange 22 of the main sliding plate 16 by means of a screw 46. It will be noted that the lock-casing 19 has a number of screw-holes 47 for securing it to the door, which is to be fastened by the lock, and that said casing 19 has screw-holes 49 and the cover plate 11 has screw-holes 49^a so that screws 50 may be inserted for holding the cover and lock-casing together. It will be noted, also, that the cover plate 11, when held in place in the lock-casing 19 by the screws 50, also holds in their proper position the sliding plates 14 and 16 by contact with the rear portion of the auxiliary sliding plate 14.

In the operation of the lock, the key 1, being inserted in the door, will control the tumblers within the barrel 2 so as to permit the rotation of the latter and, as a result, the rotation of the lock-operating arm 5, so as to bring about the rotation of the eccentric pin 12 engaging with the slot 13 in the sliding plate 14. Assuming that the lock is in unlocked position, the rotating of the eccentric pin 12 will cause the two sliding plates 14 and 16, as well as the bolts 25 and 26, to be moved forwardly until they reach their fully extended position. During this entire movement of the two sliding plates 14 and 16 and the bolts 25 and 26, the lateral stop 29, on the upper

bolt 25, is in engagement with the projection 30 in the lock-casing so that these four parts move in unison in this portion of the movement of the locking parts. As soon as the outermost position of extension of the bolts has been reached a further rotation of the key and the eccentric pin 12 does not result in the lateral movement of the main sliding plate 16 carrying the bolts 25 and 26 because of the fact that the lateral stop 29 is now in contact with the side of the lock-casing but such further rotation of the key results in the movement of the auxiliary sliding plate 14 relative to the main sliding plate 16 and the consequent rotation of the bolts 25 and 26 owing to the presence of the spiral guideways therein, which are in engagement with the upper and lower pins 23 and 24 connected to said auxiliary sliding plate. This rotation of the bolts 25 and 26 results in the lugs thereon being moved out of alignment with the rectangular opening 34 in the bolt-socket member 33 so that they engage at both sides of the same in the interior of said bolt-socket member, thus preventing the longitudinal withdrawal of said bolts 25 and 26 without first rotating them to disengage said lugs from the edges of the bolt-socket member. This rotation, furthermore, cannot be effected by merely applying a force to the periphery of the bolts owing to the particular inclination of the slots in the bolts 25 and 26. Furthermore, the bolts cannot be sawed off when so extended because of the hardened steel cores 37. In unlocking the lock the movement of key 1 in the reverse direction will rotate the bolts 25 and 26 until they are in alignment with the rectangular opening 34, and then withdraw the bolts within the lock-casing 19 by a reverse series of movement. Should anyone be in the interior of the room, or compartment, locked by the lock it is possible for him to release the lock by operating the knurled head 41 without the necessity of using a key.

While I have described my invention above in detail I wish it to be understood that many changes may be made therein without departing from the spirit of the same.

I claim:

1. A lock having a bolt and bolt-extending-and-rotating devices, comprising main and auxiliary sliding plates, a spiral connection between one of said plates and said bolt and a key actuated member adapted to move said plates by operating upon the plate having the spiral connection to the bolt.
2. A lock having a bolt and bolt-extending-and-rotating devices, so arranged that the bolt-rotating devices are brought into operation after the bolt-extending movement has been effected, comprising main and auxiliary sliding plates, a spiral connection between one of said plates and said bolt and a

key actuated member adapted to move said plates by operating upon the plate having the spiral connection to the bolt.

3. A lock having a bolt and bolt-extending-and-rotating devices, comprising main and auxiliary sliding plates, a spiral connection between one of said plates and said bolt in the form of a spiral groove on said bolt and an extension on said auxiliary sliding plate projecting therein.

4. A lock having a bolt and bolt-extending-and-rotating devices, so arranged that the bolt-rotating devices are brought into operation after the bolt-extending movement has been effected, comprising main and auxiliary sliding plates, a spiral connection between one of said plates and said bolt in the form of a spiral channel on said bolt and an extension on said auxiliary sliding plate engaging therewith.

5. A lock having a bolt and bolt-extending-and-rotating devices, comprising main and auxiliary flat sliding plates, a spiral connection between one of said plates and said bolt in the form of a spiral guideway on said bolt, an extension on said auxiliary sliding plate engaging therewith and a stop on said bolt controlling the rotary position thereof.

30 6. A lock having a bolt and bolt-extending-and-rotating devices, so arranged that the bolt-rotating devices are brought into operation after the bolt-extending movement has been effected, comprising main and auxiliary sliding plates, a spiral connection between one of said plates and said bolt in the form of a spiral guideway on said bolt, an extension on said auxiliary sliding plate engaging therewith and a lug on said bolt controlling the rotary position thereof.

7. A lock having a bolt and bolt-extending-and-rotating devices, comprising main and auxiliary sliding plates and a spiral connection between one of said plates and said bolt, the bolt being attached to the main sliding plate and the auxiliary plate being movable with regard thereto and having an arm extending into engagement with said bolt.

50 8. A lock having a bolt and bolt-extending-and-rotating devices, so arranged that the bolt-rotating devices are brought into operation after the bolt-extending movement has been effected, comprising main and auxiliary sliding plates and a spiral connection between one of said plates and said bolt, the bolt being attached to the main sliding plate and the auxiliary plate being movable with regard thereto and having an arm extending into engagement with said bolt.

9. A lock having a bolt and bolt-extending-and-rotating devices, comprising main and auxiliary sliding plates and a spiral connection between one of said plates and said bolt in the form of a spiral guideway

on said bolt and a lug on said auxiliary sliding plate engaging therewith, the bolt being attached to the main sliding plate and the auxiliary plate being movable with regard thereto.

10. A lock having a bolt and bolt-extending-and-rotating devices, so arranged that the bolt-rotating devices are brought into operation after the bolt-extending movement has been effected, comprising main and auxiliary sliding plates and a spiral connection between one of said plates and said bolt in the form of a spiral guideway on said bolt and an extension on said auxiliary sliding plate engaging therewith, the bolt being attached to the main sliding plate and the auxiliary plate being movable with regard thereto.

11. A lock having a bolt and bolt-extending-and-rotating devices, comprising main and auxiliary sliding plates and a spiral connection between one of said plates and said bolt in the form of a spiral guideway on said bolt, an extension on said auxiliary sliding plate engaging therewith and a lug on said bolt controlling the rotary position thereof, the bolt being attached to the main sliding plate and the auxiliary plate being movable with regard thereto.

12. A lock having a bolt and bolt-extending-and-rotating devices, so arranged that the bolt-rotating devices are brought into operation after the bolt-extending movement has been effected, comprising main and auxiliary sliding plates and a spiral connection between one of said plates and said bolt in the form of a spiral guideway on said bolt, an extension on said auxiliary sliding plate engaging therewith and a stop on said bolt controlling the rotary position thereof, the bolt being attached to the main sliding plate and the auxiliary plate being movable with regard thereto.

13. A lock having a plurality of bolts and bolt-extending-and-rotating devices, comprising main and auxiliary sliding plates and a spiral connection between one of said plates and said bolts, the bolts being carried by the main sliding plate and the auxiliary plate being movable with regard thereto and having an arm extending into engagement with said bolts, and a locking plate for securing the bolts and sliding plates together.

14. A lock having a plurality of bolts and bolt-extending-and-rotating devices, so arranged that the bolt-rotating devices are brought into operation after the bolt-extending movement has been effected, comprising main and auxiliary sliding plates and a spiral connection between one of said plates and said bolts, the bolts being carried by the main sliding plate and the auxiliary plate being movable with regard thereto and having an arm extending into engagement

4
with said bolts, and a locking plate for securing the bolts and sliding plates together.

15. A lock having a plurality of bolts and bolt-extending-and-rotating devices, comprising main and auxiliary sliding plates and a spiral connection between one of said plates and said bolts in the form of a spiral guideway on the bolts and an extension on said auxiliary sliding plate engaging therewith, the bolts being carried by the main sliding plate and the auxiliary plate being movable with regard thereto, and a locking plate for securing the bolts and sliding plates together.

16. A lock having a plurality of bolts and bolt-extending-and-rotating devices, so arranged that the bolt-rotating devices are brought into operation after the bolt-extending movement has been effected, comprising main and auxiliary sliding plates and a spiral connection between one of said plates and said bolts in the form of a spiral guideway on said bolts and an extension on said auxiliary sliding plate engaging therewith, the bolts being carried by the main sliding plate and the auxiliary plate being movable with regard thereto, and a locking plate for securing the bolts and sliding plates together.

17. A lock having a plurality of bolts and bolt-extending-and-rotating devices, comprising main and auxiliary sliding plates and a spiral connection between one of said plates and said bolts in the form of a spiral guideway on said bolts, an extension on said auxiliary sliding plate engaging therewith and a stop on said bolts controlling the rotary position thereof, the bolts being carried by the main sliding plate and the auxiliary plate being movable with regard thereto, and a locking plate for securing the bolts and sliding plates together.

18. A lock having a plurality of bolts and bolt-extending-and-rotating devices, so arranged that the bolt-rotating devices are

brought into operation after the bolt-extending movement has been effected, comprising main and auxiliary sliding plates and a spiral connection between one of said plates and said bolts in the form of a spiral 50 guideway on said bolts, an extension on said auxiliary sliding plates engaging therewith and a stop on said bolts controlling the rotary position thereof, the bolts being carried by the main sliding plate and the auxiliary 55 plate being movable with regard thereto, and a locking plate for securing the bolts and sliding plates together.

19. A lock having a bolt, and bolt extending and rotating devices comprising main and auxiliary sliding plates, a spiral connection between one of said plates and said bolt, the latter having a hard steel core adjacent exposed portions of the bolt when in locking position, and a key actuated member 60 adapted to move said plates by operating upon the plate having the spiral connection to the bolt.

20. A lock having a plurality of bolts and bolt extending and rotating devices for 70 operating the same, comprising main and auxiliary sliding plates, and spiral connections between one of said plates and said bolts.

21. A lock having a bolt, means including 75 a plate for controlling the forward direction of movement of the bolt, and a sliding plate having a spiral connection with said bolt for rotating the same.

22. A lock having a bolt, means including 80 a plate for controlling the forward direction of movement of the bolt, a sliding plate having a spiral connection with said bolt for rotating the same, and an oscillating crank for controlling the movement of 85 the sliding plate.

In testimony that I claim the foregoing, I have hereunto set my hand this 12 day of June, 1922.

HERMAN HANSEN
